UNITED STATES PATENT OFFICE.

EDMUND L. BULLOCK, OF HARTFORD, CONNECTICUT, ASSIGNOR OF ONE-HALF TO WALTER A. RILEY, OF SAME PLACE.

DISH-WASHER.

SPECIFICATION forming part of Letters Patent No. 240,654, dated April 26, 1881.

Application filed January 10, 1881. (No model.)

To all whom it may concern:

Be it known that I, EDMUND L. BULLOCK, of Hartford, in the county of Hartford and State of Connecticut, have invented a certain 5 new and useful Improvement in Dish-Washers, of which the following is a description, reference being had to the accompanying drawings, where—

Figure 1 is an exterior view of a washer 10 embodying my said improvement. Fig. 2 is a top view of same with the covers or cover-sections removed. Fig. 3 is a view of same, in central vertical section, on plane $x x$, Fig. 2.

The object of the improvement is the production of an apparatus of extreme simplicity, 15 cheapness, and efficiency for facilitating the washing of dishes, one of such construction that it can profitably be made and used in a size sufficiently small for common families.

20 The letter a denotes a case for containing the articles to be washed, also the washing material, also the rotating cage which carries the articles to be washed. It is essential that its shape be such as to permit the cage to rotate horizontally or in a horizontal plane within it. The cover of this case is in two sections, $b b$, so as to permit the shaft of the rotary cage to pass up and out between them, and so as to permit the bearing-brace c , which is 25 supported at its ends on the case, and centrally forms a bearing for the shaft of the rotary cage, to be located between them.

The letter d denotes the rotary cage as a 30 whole, of which it is an essential feature that it shall rotate in a horizontal plane, which gives an opportunity to place articles in it in the simplest and easiest manner possible, the top being left open for that purpose, and the bottom substantially closed to give a support 35 to such articles. Moreover, the articles do not need that particular fastening which would be necessary if the cage rotated vertically, for if they become loosened they cannot fall. Moreover, in rotating the articles are constantly in 40 the water. Moreover, the shaft does not need any packing when it passes out of the case. Moreover, on removing a cover the condition of all the articles being washed can be seen at a

glance. Moreover, an excess in weight of articles on one side does not materially affect 50 the ease of rotation. This cage is composed of a bottom for supporting most of the articles, an exterior annular open-work band, and interior cross-supports. It is made fast to the shaft e , the upper end of which is cranked, 55 whereby to rotate it. By taking hold of this shaft, it and the cage can be lifted out together, making of the cage and the shaft a sort of basket and handle, which can be filled with articles to be washed, set into place in the casing, filled with hot water, and rotated till the articles are cleansed, and then lifted out so 60 that the articles can be handily removed. The bearing-brace c rests by its ends in mortises made in the outer casing, a , and, when 65 constructed as shown in the drawings, may be lifted with the cage and shaft.

Plates and the like are set edgewise between the cross-supports $f g h$. Some of these, f , are formed into loops vertically to receive 70 thereon tea-cups and the like. Others of them, g , are formed into loops horizontally or laterally, to take and hold between them knives, forks, and the like. These lateral loops are formed of elastic wire, so as to pinch and sufficiently hold knives and the like that are put 75 into their embrâe.

The cranked handle is made fast to the cage, that it may serve like a basket-handle in lifting the cage out of the outer casing. The 80 cover-sections are each made separately removable from the casing, to permit the use of a light central bearing-brace for the axle and to allow access to the interior without removing the crank.

I claim as my invention—

In combination, the casing a , the removable cage d , provided with the cranked handle fast thereto, the removable bearing-brace c , and the separately removable cover-sections b 90 b , all substantially as described, and for the purpose set forth.

EDMUND L. BULLOCK.
